[57] CLAIM

The ornamental design for a cursor control with pistol grip, as shown and described.

DESCRIPTION

FIG. 1 is a perspective view of the cursor control with pistol grip showing my new design;

FIG. 2 is a top plan view of the device;

FIG. 3 is a bottom plan view of the device;

FIG. 4 is a front elevational view of the device;

FIG. 5 is a rear elevational view of the device;

FIG. 6 is a right side elevational view of the device; and,

FIG. 7 is a left side elevational view of the device.

The cord is broken away to show an indeterminate length in the views for ease of illustration only.
